INVENTOR
Chester K. Hann
BY Chester C. Shephard

ATTORNEY.

UNITED STATES PATENT OFFICE.

CHESTER K. HANN, OF COLUMBUS, OHIO.

WINDOW-SCREEN.

SPECIFICATION forming part of Letters Patent No. 443,092, dated December 23, 1890.

Application filed December 14, 1889. Serial No. 333,778. (No model.)

To all whom it may concern:

Be it known that I, CHESTER K. HANN, a citizen of the United States, residing at Columbus, in the county of Franklin and State 5 of Ohio, have invented a certain new and useful Improvement in Window - Screens, of which the following is a specification.

My invention relates to the improvement of window-screens, and has particular relation 10 to the improvement of the device shown in my former application, Serial No. 317,358, allowed on the 25th day of November, 1889.

The objects of my present invention are to so construct and arrange a window-screen of 15 this class as to admit of its parts being readily and easily adjusted for use in windows of different widths, to produce a spring-actuated screen of superior construction without the use of the ordinary spring-curtain roller, to 20 simplify the construction shown in said former application, to produce a superior form of adjustable case and caps therefor, and to provide guides for the edges of the screen. These objects I accomplish in the manner 25 illustrated in the accompanying drawings, in which—

Figure 1 is an interior elevation of a window having my improved screen thereon and showing the lower window partially raised. 30 Fig. 2 is a central vertical section of the same. Fig. 3 is a sectional view taken on line $v v$ of Fig. 4. Fig. 4 is a longitudinal central section of the roller-case, showing the roller in elevation therein and its screen removed therefrom. 35 Fig. 5 is a side elevation of one of the cover-caps. Fig. 6 is a view in elevation of a portion of the cover-case. Fig. 7 is a transverse section of the same. Fig. 8 is a transverse section of the screen end strip, taken on line $x x$ of Fig. 1. Fig. 9 is a transverse section 40 one of the side pieces of the window-frame, taken on line $z z$ of Fig. 1 to show the screen-guide. Fig. 10 is a view in perspective of a window-sash strip which I use in connection 45 with my device; and Fig. 11 is a transverse section taken on line $y y$ of Fig. 4, showing in addition the screen wound upon the roller. Fig. 12 is a detail view in perspective of one 50 of the roller-pivot pins.

Similar letters refer to similar parts throughout the several views.

a represents a roller of the general form of

a curtain-roller. This roller is divided at or near its central portion to form two sections, the inner end of one of said sections having a socket 55 and the adjoining end of the remaining section being cut away to form a pin or dowel b . The two sections of the roller are joined, as shown, by having the dowel of one section inserted the desired distance within the socket 60 of the other, said sections being held in this position by means of suitable tacks or pins c , which extend through the wall of the socket and into the dowel.

The outer end of each of the sections of the 65 roller a is provided with a pin-socket d , the latter being square or angular in cross-section.

Upon the roller a is wound and secured at one end a screen f , said screen being formed 70 of any desired flexible material.

Surrounding the roller a and the screen f wound thereon is a cylindrical case or cover g , which is preferably formed of thin metal, and which is formed, as shown, throughout its length with a longitudinal slot g' . The 75 longitudinal edges of the case g , produced by the formation of the slot g' , are, as shown in Figs. 6 and 7 of the drawings, bent over until in close proximity to the outer surface of the case, thus forming stop-grooves h , for 80 the purpose hereinafter specified. The case g is also formed in two sections, the inner ends of said sections being adjustably connected by means of a collar i , which is of the same form in cross-section as the case-sections, with the exception that the stop-grooves 85 are omitted, and has its longitudinal edges entering and abutting against the stop-grooves h . This collar is of such circumference as to inclose the inner ends of the case. 90

k represent case end caps, one of which is adapted to fit over each of the outer ends of the case-section. Each of these caps, consists of a disk provided with a circumferential flange, and is made to inclose, as shown, a 95 coil-spring. One end of this coiled spring is riveted or otherwise secured to the inner face of the cap-flange, while its remaining end is secured to a pin n , the latter having one of its ends, which is round in cross-section, journaled in the center of the cap k , from which it projects inwardly and having its remaining end, which is square in cross-section, as shown in Fig. 12 of the drawings, entering 100

the socket *d* of the roller. The flange of the cap *k* is provided with an open slot *k'*.

The screen *f* has one of its ends secured to the roller *a*, and passing outward through the 5 slot of the case has its remaining end secured to an adjustable cross-strip *q*. This cross-strip *q* is, as shown, formed of two sections, each of which is bent somewhat in the form of a block letter **C**, and one of which is 10 of such size as to fit and slide snugly within the other, as shown in Fig. 8 in detail of the drawings. The outer end of the screen is clamped firmly between the bent edges and the bodies of the strip-sections *q*. One of the 15 caps *k* is slipped over each end of the case *g*, the pin *n* extending within the socket *d* of the roller, and the parallel edges of the cap formed by the slot *k'* are made to enter and abut against the stop-grooves *h*, in order to 20 place the spring *l* and the roller with which it is connected by the spring *m* under spring-tension. The case adjoining its slot *g'* is temporarily pressed or sprung inward from engagement with the cap to admit of said 25 cap being rotated a sufficient number of times to coil the spring *l* more tightly about its pin *n*. The edges of the slot *k'* are then brought again into engagement with the stop-groove to prevent the rotation of said 30 cap. Secured to and formed on the periphery of each of the caps *k* is a projecting lug *k*².

Although, as will hereinafter be seen, my improved screen and its parts may be used at either end of a window, for convenience 35 I have shown and described the screen which is adapted to be used in connection with the lower sash.

The herein-described case and inclosed roller is secured upon the window seat or sill 40 *a* by inserting projecting lugs or feet *k*² beneath the heads or staples *k*³, the latter being driven into the window-sill. In so locating the case its slot *g'* is made to face the sash. The screen passing outward through 45 the slotted openings *k'* is made to pass upward, its edges extending within the open vertical slots or grooves of vertical guide-strips *s*, one of which is secured to the inner face of each of the inner window-strips *t*. The cross- 50 strips *q* of the screen are provided with eyes *q'*, with which are made to engage the upwardly-projecting hooks *q*² of the lower cross-piece of the lower sash. It is obvious, however, that the screen-strip may be detachably secured or connected in any desired manner different from that herein described. 55 From the construction herein shown and described it will readily be seen that the raising of the lower sash *y* will result in the screen being pulled upward with said lower sash and the opening beneath the same being completely closed by the screen.

In order to close the space which exists between the upper and lower sash when the 65 lower sash is not entirely raised, I employ a

transverse flexible strip *r*, preferably of thin rubber, said strip being secured to the under side of the upper sash *w*, and of such width as to project inwardly and into contact with the glass of the lower sash, as is shown more clearly in Fig. 2 of the drawings.

Owing to the fact that the two sections of the case *g* are connected by a central collar *i*, it is obvious that the sections may be drawn from or pushed toward each other to lengthen 75 or shorten the case to adjust it for use in window-frames in different widths. By removing tacks *c*, which connect the two sections of the roller *a*, the length of said roller may be changed by pulling outward or inward said sections and again connecting the same by said tacks when at the desired length.

The screen cross-strip *q* being formed in sections, which slide one within the other, it is evident that a similar adjustment may be 85 made of said cross-strip.

From the construction shown and described it will be seen that as the screen is drawn upward from its case the revolution of the roller caused thereby will impart a rotary motion 90 to the pin ends, which, through their connection with the springs *l*, will operate to increase the tension of the latter. This tension of the springs will result in the prompt taking up or winding of the screen upon the roller as 95 the sash is lowered.

It is evident that one of my improved screens may be used in connection with the upper sash by securing the case *g* to the upper end of the window-frame and making the 100 same connection of the screen and upper sash as that described for the lower sash.

During the winter months, or at times when the screen is not considered necessary, it may be detached from the sash and its case withdrawn from its connection with the window-frame.

By the construction and arrangement herein shown and described it will readily be seen that the means of accomplishing said adjustments are simple in form, inexpensive, and do not mar the appearance of the device.

Having now fully described my invention, what I claim, and desire to secure by Letters Patent, is—

In a window-screen, the combination, with the roller *a*, having adjustable sections and end pin-sockets, screen *f*, secured and wound upon said roller, slotted case *g*, formed of sections of equal diameters, and slotted collar *i*, adjustably connecting said case-sections, of slotted case-caps *k*, pins *n*, entering sockets *d*, and coiled springs *l*, connecting said pins and caps, substantially as and for the object set forth.

CHESTER K. HANN.

In presence of—

C. C. SHEPHERD,
BARTON GRIFFITH.
